MANUFACTURE OF PAPER-DISK BOTTLE CAPS

William Gordon Southam, Montreal, Quebec,
Canada, assignor to Southam Press Montreal
Limited, Montreal, Quebec, Canada

Application May 17, 1939, Serial No. 274,257
In Canada April 13, 1939

3 Claims. (Cl. 93—1.3)

This invention relates to improvements in the manufacture of paper-disk bottle caps provided with integral pull-tabs and has for its object the provision of improved means for effecting the so-called stripping operation which consists in separating from the body of the cap that portion of the integral tab which is outlined in the usual manner by cutting part way through the thickness of the paper stock.

In making the bottle caps of the type mentioned herein it is customary to remove a small portion of the paper stock to provide a recess having one wall formed by that end of the outlined tab which is separated from the body of the cap during the stripping operation. The main purpose of this recess is to facilitate raising of the tab after it has been restored to its original position following the stripping operation.

According to the present invention the stripping of the tab from the body of the cap is accomplished by directing a blast of air against the end of the outlined tab which is exposed by the formation of the above mentioned recess. The stripping action of the air blast serves to separate the outlined portion of the tab from the body of the cap along a plane of cleavage located between and parallel with the upper and lower surfaces of the cap, the distance between the upper surface of the cap and said plane of cleavage being predetermined by the depth to which the cap is cut in outlining the tab.

This method of accomplishing the stripping operation has several important advantages over known methods involving the use of mechanically actuated stripping tools which are brought into direct engagement with the paper stock during the stripping operation. One objection to the use of mechanically actuated stripping tools is that they tend to tear or otherwise injure or damage the paper stock during the stripping operation. Another objection is that the use of these tools introduces various mechanical difficulties which add materially to the cost of manufacture. These and other objections are eliminated when the stripping operation is accomplished with the aid of an air blast in accordance with the present invention.

The accompanying drawing is a perspective view illustrating one practical embodiment of the invention.

Referring more particularly to the drawing, 5 designates a pneumatic tab stripping mechanism including a base 6 having its upper surface recessed to provide a longitudinally extending guide groove 7. A transversely extending pipe 8 is

clamped in a bracket 9 mounted on the base at one side of groove 7. One end of this pipe is bent in the longitudinal direction of the base to provide a nozzle extension 10 having its discharge opening 11 centered between the side walls of the 5 groove. The other end of pipe 8 is connected, through flexible tube 12 and valve 13, to a compressed air supply line 14. The casing of valve 13 is provided with a vertical valve bore 15 and an intersecting horizontal bore 16, the latter forming a connecting passage between tube 12 and supply line 14. A cylindrical valve plug 17 is slidably mounted in valve bore 16 and is provided with an annular groove or port 18. A spring 19 acts against a head 20 at the upper end of plug 15 17 and normally serves to hold the latter in an elevated or valve closing position. In this position of plug 17 the annular groove or port 18 is located above the horizontal bore or air passage 16. At suitably timed intervals the valve plug 17 20 is depressed by a cam 22 so that the annular groove or port 18 is aligned with the horizontal bore or air passage 16. In this open position of the valve compressed air passes from the supply line 14 through port 16 and tube 12 to pipe 8 and 25 is discharged through the opening 11 of the nozzle extension 10.

At this point it is deemed advisable to refer briefly to the series of operations ordinarily followed in producing paper-disk bottle caps of the 30 type with which this invention is concerned. Such caps are formed from a blank comprising a travelling strip of paper or cardboard such as that indicated at 23 in the present drawing. The initial operation in the formation of each cap 35 consists in removing a portion of the stock from the upper surface of the blank to provide a recess 24. In the next operation the upper surface of the blank is cut as indicated at 25 to outline the sides and one end of the pull tab 26, it being noted 40 that the outlined end of the tab forms one wall of the recess 24. The next operation is the stripping operation which consists in separating the outlined portion of the tab blank from the body portion of the blank. The blank is then passed to 45 a stapling mechanism which serves to drive a staple 27 through the blank at the base of each tab. The final operation consists in punching from the blank a plurality of circular disks or bottle caps 28 each including within its boundaries 50 a pull tab 26 and the adjoining recess 24. Other operations, such as the return of each pull tab to its normal flat position after being raised by the stripping operation and the waxing of the blank, also form part of the complete process of manu- 55

feature but have no particular bearing on the present invention.

The pneumatic stripping mechanism provided in accordance with the present invention is preferably located between the tab outlining mechanism and the stapling mechanism. As the blank comes from the tab outlining mechanism it is passed through the groove 7 of base 8 on its way to the stapling mechanism. Since the blank 10 travels in the direction indicated by the arrow it will be noted that the outlined end of each pull tab 26 and the adjacent recess 24 passes directly beneath the nozzle opening 11. As each tab 26 reaches a position approximating that indicated 15 at X the valve 13 is opened so that a blast of compressed air is directed into the recess 24 and against the adjacent outlined end of the tab 26 with sufficient force to separate or strip the outlined portion of the tab from the body of the blank, the plane of cleavage between the outlined portion of the tab and the body of the blank being 20 parallel with the upper face of the blank and being at a depth determined by the depth of the tab outlining cut or incision 25.

25 While I have described one practical embodiment of this invention it will be understood that the essential feature resides in the utilization of an air blast for stripping the outlined pull tab of each cap from the body of the cap or cap forming blank. It will therefore be understood that the invention is not restricted to the specific embodiment illustrated in the present drawing but may

be reduced to practice in various other ways within the scope and spirit of the appended claims.

Having thus described my invention, what I claim is:

1. That step in the manufacture of a paper-disk bottle cap which is cut to a depth less than the thickness of the paper stock to outline the sides and one end of an integral pull-tab which comprises stripping or separating the so outlined portion of the tab from the body of the stock by directing a blast of air against the outlined end of the tab. 5

2. In the manufacture of a paper-disk bottle cap provided with an integral pull-tab the steps which consist in cutting the cap to a depth less than the thickness of the paper stock to outline the sides and one end of the tab and then separating the so outlined tab from the body of the stock by directing a blast of air against the outlined end of the tab. 15

3. In the manufacture of a paper-disk bottle cap provided with an integral pull tab the steps which consist in removing a small portion of the paper stock to provide a recess in the upper surface of the cap, then cutting the cap to a depth less than the thickness of the stock to outline the sides and one end of a pull-tab so that the outlined end of the tab forms one wall of said recess and then separating the outlined tab portion from the body of the cap by directing a blast of air into 25 said recess and against the adjacent outlined end of the tab. 30

WILLIAM GORDON SOUTHAM.
